CONTROL SYSTEM FOR AIR COMPRESSORS

Allen C. Staley, Birmingham, Mich., assignor to
 Chrysler Corporation, Detroit, Mich., a corporation of Delaware

Application October 2, 1933, Serial No. 691,813

6 Claims. (Cl. 230—4)

This invention relates to power driven air compressors and more especially to control mechanism for regulating the operation of the same.

The main object of the invention is to improve

5 the operation of a power driven air compressor.

A further object is to increase the efficiency of an air compressor.

Another object is to so control an air compressor that it will operate at speeds in proportion to the demand for air.

Another object is to reduce the operating cost of an air compressor per cubic foot of air delivered.

Another object is to provide for a high volumetric efficiency at normal operating speeds of an air compressor.

Another object is to reduce the temperature of the air delivered by an air compressor.

Another object is to avoid throttling of air supplied to an air compressor.

A still further object is to avoid hunting or fluttering in the control of the operation of an air compressor.

Other objects and advantages will become apparent from the following description and appended claims.

According to one aspect, this invention involves the control of a multicylinder air compressor operable by a multicylinder internal combustion engine at speeds covering a wider range than customarily employed and at considerably higher speeds than usual when operating at or near full capacity. The compressor is loaded or unloaded by a load control valve placed in the intake thereof and operable to fully open position and to fully closed positions. With the compressor loaded, the speed of the engine is controlled by a speed governing mechanism adapted to control the intake throttle valve of its carburetor and the speed governing mechanism is under the control of pressure responsive mechanism operable in accordance with increasing or decreasing pressures above a predetermined point in an air tank, to which compressed air is supplied by the air compressor, to act on the speed governing mechanism gradually to cut down or increase the speed of the engine. Pressure above a higher predetermined point in the air tank causes means operable by the pressure responsive means, at one limit of its operation, to act on valve operating means and cause the load control valve in the intake of the compressor to assume its fully closed position to unload the compressor. A drop in pressure in the air tank to a third predetermined value somewhat less than said second-

named predetermined value causes the pressure responsive means to allow the valve operating means to open the load control valve and load the compressor.

According to another aspect, the invention involves the control of an air compressor so that it is loaded from approximately one quarter to full capacity, giving low speeds and low friction during part capacity operation and during almost wide open throttle operation of the engine by which the compressor is operated while at full capacity. This effects a considerable economy of fuel and increased life of equipment as compared with compressors employing control systems of the type that vary the amount of idle operation so that a certain per cent of idling is always used up until full capacity operation is reached. The present system causes idling only when the compressor is operating at a small fraction of full capacity and results in a saving of up to fifty per cent in fuel consumption.

For the purpose of illustrating the genus of the invention, a typical concrete embodiment is shown in the accompanying drawings in connection with a portable compressor unit.

In the drawings:
 Figure 1 is a top plan, more or less diagrammatic in form, and with parts broken away to show interior parts, of a portable compressor unit in the form of a trailer and embodying a control system in accordance with the principles of this invention;

Fig. 2 is a section taken on the line 2—2 of Fig. 1, certain portions being shown in elevation;

Fig. 3 is a section taken on the line 3—3 of Fig. 2, parts being broken away and shown in sections;

Fig. 4 is a section taken on the line 4—4 of Fig. 3;

Fig. 5 is a section taken on the line 5—5 of Fig. 1;

Fig. 6 is a section taken on the line 6—6 of Fig. 5;

Fig. 7 is a graphical representation showing air delivery and air pressure curves as plotted against various operating speeds of the compressor, and

Fig. 8 is a diagrammatic representation of the control units, shown in Figs. 1 to 6, as interrelated for regulating the operation of the compressor, the various parts of the control system and associated mechanism being indicated by legend.

Referring to Fig. 1 in which is depicted a portable compressor unit in the form of a trailer, the numeral 10 indicates the trailer frame supported

by a wheel and axle assembly 11. Upon opposite sides of the frame 10 are supported an engine 12 and a compressor 13 connected by a suitable drive and speed reduction means such as a pair of drums 14 and 15 and a plurality of V belts 16 extending therebetween, the pulley 14 being of a smaller diameter than the pulley 15 in the ratio of approximately 1 to 1.59 to reduce the operating speed of the compressor by approximately this ratio. The engine 12 and compressor 13 each includes the same size cylinder block of a conventional four cylinder industrial engine of the four cycle type with the cylinders, cast in block integral with the crank case so that the engine and compressor are of the same size and are made up largely of interchangeable parts to make servicing of these units a simple problem. Each of these units is provided with an individual cooling system including a radiator 17 and fan 18. The compressor is provided with an intake manifold 20 adapted to draw in air through a conduit 21 in which is disposed a load control valve 22, shown more in detail in Figs. 5 and 6, and which will later be more fully described. The compressor 13 delivers air through an exhaust manifold 23 connected to the individual cylinders of the compressor and through a delivery conduit 24 communicating with an air tank 25 supported between converging portions of the side rails of frame 10. The air tank 25 is provided with a plurality of delivery valves 26 for supplying air to air driven devices, such as for example, from one to four air drills or similar air driven tools. A conduit 27 communicates between the air tank 25 and a pressure responsive mechanism 30 adapted to cooperate with a speed control mechanism for the engine 12 or other motive means for driving the compressor 13. The pressure responsive device 30 and the speed control means 31 are shown more in detail in Figs. 2 and 3. The pressure responsive device 30 also controls the operation of a switch 32 which in turn controls the operation of operating means for the valve 22 in the intake conduit 21 of the compressor.

Reference may now be had to Figs. 2, 3 and 4 which illustrate the construction and arrangement of the pressure responsive device, the speed control mechanism for controlling the operation of the motive means for the compressor, and the switch for controlling the operation of the intake valve for the compressor. The units 30, 31 and 32 are mounted on a plate 33 fixed to the block of engine 12. The unit 30 is in the form of a cylinder in which is disposed a movable piston on preferably a sylphon bellows 34 normally biased to the right hand end position as viewed in Fig. 2 by means of a spring 35. The conduit 27 communicating with the air tank 25 is connected to a cylinder head 36 for the casing of the pressure responsive device 30 so that the pressure within the tank 25 is impressed upon the head surface 37 of the bellows 34 whereby a sufficient pressure within the air tank will overcome the biasing action of the spring 35 and move the head surface of bellows 34 to the left as viewed in Fig. 2. A piston rod 40 connects the head surface of bellows 34 with a lever 41 disposed exteriorly of the pressure responsive device and pivoted to the plate member 33 by means of a pivot pin 43 supported in a bracket 44 fixed to the plate 33.

The speed control mechanism 31 is in the form of a governor or other speed control device operable by the engine 12 or the compressor 13 and includes a control arm 50 adapted to rotate in a clockwise direction as viewed in Fig. 2 in re-

sponse to increasing speeds of the motive means 12. The speed control mechanism 31, as illustrated, is operated by means of a gear 51 from the engine 12 and in response to higher speeds of the engine rotates the arm 50 in a clockwise direction against the tension of a governor spring 52 connecting an arm 53 of the control lever 50 to the lever 41. The outer end of the arm 50 may be connected by means of a link 54 to the throttle valve of the carburetor 38 for supplying fuel to the engine 12 so as to control the speed of the latter. It will be noted that the control lever 50 is connected by the arm 53 and spring 52 to the lever 41 so that increased pressures within the tank 25 will cause movement of the head surface 15 of bellows 34 against the tension of spring 35 and will cause clockwise rotation of the lever 41 and rotation of lever 50 in a similar direction to reduce the speed of the engine 12. The lever 41 is fixed against relative rotation to the pivot pin 20 43 and serves not only to rotate the control lever 50 in the event of high pressures within the tank 25 but also at certain predetermined pressures in tank 25 to actuate the switch 32. To this end an arm 55 is also fixed against relative rotation upon the pivot pin 43 and is provided with an adjustable screw 56 upon the free end of this lever arm cooperable with a contact arm 57 pivoted upon a switch bracket 59 by means of the pivot pin 58. The switch bracket 59 carries a 30 terminal 60 for a circuit, (Fig. 8), to which the switch 32 is connected. The contact arm 57 carries a movable contact 61 cooperable with a contact 62 carried on a spring arm 63 mounted on a switch bracket 64 but insulated therefrom by 35 insulation means 65. The spring arm 63 carries a flexible spring leaf 66 cooperable with a similar leaf 67 connected to one end of the winding of an electro-magnet 70 disposed beneath the spring arm 63 and positioned to actuate the same to a 40 depressed position. The opposite end of the winding 70 carries a terminal 71 so that the switch 32 may be connected with the previously mentioned circuit by means of the terminals 60 and 71. A spring 72 normally urges the contact arm 45 57 upwardly as viewed in Fig. 4 to maintain the movable contact 61 in engagement with the contact 62 carried by the spring arm 63 and these contacts are always in engagement when the winding of the electro-magnet 70 is energized except as the contacts 61 and 62 may be mechanically separated by the adjustable screw 56 carried by the lever arm 55. The purpose of the electro-magnet 70 is to exert a pull on the spring arm 63 to depress the contact end of the same 55 while rotating the contact arm 57 so that both contacts 61 and 62 are depressed whenever the electro-magnet 70 is energized. The depression of the spring arm 63 together with the contacts 61 and 62 and the contact arm 57 rotates the contact arm in a counter-clockwise direction as viewed in Fig. 2 and away from the lever arm 55 and adjustable screw 56 so that a higher pressure must be reached within the tank 25 for the screw 56 to break the contacts 61 and 62 than 60 would be the case if the electro-magnet 70 were not energized.

With the electro-magnet 70 de-energized the resiliency of the spring arm 63 urges it upwardly as viewed in Fig. 4 against a stop 73 shown in 70 Figs. 2, 3 and 8. The spring 72 urges the contact arm 57 in a clockwise direction to maintain the contacts 61 and 62 in engagement unless the contact 61 is mechanically held in separated position by means of the screw 56 carried by the arm 55 75

and operable by the lever 41. The resiliency of the arm 63 also serves to cause a snap break of the contacts 61 and 62 when the circuit through switch 32 is mechanically broken by the adjustable screw 56 carried by the lever 55. This snap action prevents severe arcing at the contacts and burning out of the latter.

When the pressure in tank 25 reaches a certain predetermined value, the arm 41 and lever arm 55 will be rotated in a clockwise direction as viewed in Fig. 2 until the screw 56 mechanically separates the contact 61 from the contact 62 de-energizing the circuit through the switch 32 allowing the spring arm 63 to snap away from the armature of the electro-magnet 70 and against the stop 73. Upon retractive movement of the lever 41, i. e., rotation of the lever 41 and lever arm 55 in a counter-clockwise direction, this lever and lever arm must rotate to a position corresponding to a lower pressure in the tank 25 before the contact arm 57 can allow the movable contact 61 again to engage the contact 62 to complete the circuit through the switch and again energize the electro-magnet 70. Energization of the electro-magnet 70 will again depress the spring arm 63 but the contacts 61 and 62 will remain in engagement since the lever arm 55 and stop 56 are receding away from the switch arm 57. In this manner the switch 32 is open at a higher pressure within the tank 25 than the pressure within the tank at which the switch will again close. This operation of the switch 32 avoids fluttering or hunting of the control of the load control valve 22 of the compressor 13.

The switch 32 is employed to control the operation of the load control valve 22 for the compressor 13. Referring to Figs. 5 and 6 in which this valve is shown more in detail, the valve includes a body 80 provided with a cylindrical bore 81 adapted to extend between the bore of the intake conduit 21 and the intake manifold 20. A disc valve 82 is arranged within the cylindrical bore 81 and rotatably mounted on a pivot pin 84 by fastening the disc valve within a radially extending slot 83 projecting through the axis of the shaft by means of screws 85. The valve element 82 is adapted to be operated to two positions, one position being the fully open position illustrated in Figs. 5 and 6 in which the element 82 is arranged axially of the cylindrical bore 81 and the other position of the valve element being at right angles to the illustrated position in which the valve disc 82 fully closes the cylindrical bore 81, (vertical position of valve disc, Fig. 8) in which position it is disposed normally with respect to the axis of the cylindrical bore 81. The valve disc 82 is adapted to be operated to the fully open position illustrated in Figs. 5 and 6 by means of a solenoid 86 including a movable armature 87 connected by an adjustable link 90 to a double arm lever 91 fixed to the shaft 84. The solenoid 86 is adapted to operate the disc valve element 82 against the bias of a spring 88 extending between the body member 80 and the opposite arm of the lever 91 from that arm to which the link 90 is connected. The solenoid 86 has its winding connected in series in the above mentioned circuit, (Fig. 8), and the contacts 61 and 62 are connected in series with the winding of solenoid 86 so that the valve disc 82 is in open position whenever the circuit is energized and the contacts 61 and 62 are closed. The energization of the circuit or opening of the contacts 61 and 62 de-energizes the solenoid 86 and throws the control

of the valve upon the spring 88 which operates the valve to the fully closed position.

Referring to the figures previously described, to the graphical representation shown in Fig. 7, and to the diagrammatic view shown in Fig. 8, the operation of the compressor will be described. The engine 12 operates the compressor 13 through the V belt drive means 14, 15 and 16 so that the compressor is operated continuously at speeds in proportion to the demand by air from the air tank 25. Upon starting the engine 12 it accelerates until a speed is reached for which the speed governing device 31 is set. This speed may be, for example, 1200 R. P. M. of the compressor. Any tendency of the engine 12 to operate at higher speeds will cause the speed governing mechanism 31 to rotate the control lever 50 in a clockwise direction against the tension of the spring 52 and through the link 54, restrict the delivery of fuel to the carbureting mechanism 38 of the engine 12 to reduce its speed to the value for which the speed governing mechanism 31 is set. With little or no delivery of air from the air tank 25, the pressure within this tank will be built up to a value of approximately 80 pounds per square inch when the speed of rotation of the compressor has reached approximately 1200 R. P. M. Continued rotation of the compressor will build up higher pressures within the air tank and pressures above 80 pounds per square inch will be communicated to the head surface 37 of the bellows 34 and overcome the biasing action of the spring 35 so that the bellows 34 will move to the left as viewed in Figs. 2 and 8. This movement of the bellows 34 will cause clockwise rotation of the lever 41 and through the spring 52 and arm 53 will cause a corresponding rotation of the arm 50 which will in turn cause a reduction of the amount of fuel admitted to the engine 12 and a reduction in its speed. The circuit 95 containing the switch 32 and the winding of the solenoid 86 in series with contacts 61 and 62 is energized during the operation of the engine 12 from a storage battery 96 and controlled by a switch 97 which may be the ignition switch for engine 12. Since at lower speeds of the engine and at lower pressures within the tank 25 the stop screw 56 is spaced from the switch arm 57, the contacts 61 and 62 are closed and the winding of the solenoid 86 is energized so that the intake valve 22 is maintained at fully open position. As the pressure within the tank 25 is built up from approximately 80 pounds per square inch to a value of approximately 105 pounds pressure, the piston 37 is gradually moved to the left as viewed in Fig. 2, causing clockwise rotation of the control lever 50 of the speed governing mechanism and consequent reduction of the fuel delivered to the engine 12 and a reduction in its speed. With little or no demand for air from the tank 25 the speed of rotation of the compressor will have been gradually reduced to a value of approximately 510 R. P. M. When a pressure of 105 pounds per square inch is attained within the air tank 25 the adjustable stop screw 56 will have made contact with the pivoted contact arm 57 of the switch 32 and pressures above 105 pounds within the tank 25 will depress the contact lever 51 and open the contacts 61 and 62. As these contacts are mechanically opened, the energization of the winding of the electro-magnet 70 is cut off and the spring arm 63 will snap to an elevated position against the stop 73 which snap action of the contact and the rapid separation of the same will reduce arcing and burning out of these contacts. Separation of the contacts 75

61 and 62 will cause de-energization of the winding of the solenoid 86 and throw the control of the load control valve 22 upon the spring 92 which causes a closing of the valve disc 82 shutting off further delivery of air to the air compressor.

5 As long as the pressure within the tank 25 remains above, for example 97 to 100 pounds per square inch, the engine and compressor will operate at idling speed with the load control valve 22 of the compressor in fully closed position. If 10 the pressure within the air tank 25 is reduced through the delivery of air or leakage or other causes, the pressure within the pressure responsive means 30 is also reduced allowing the piston 15 to move to the right under the influence of the spring 35 which allows counter-clockwise rotation of the lever 41 and clockwise rotation of the contact arm 57 of the switch 32. The contact arm 57 follows the screw 56 until the contacts 20 61 and 62 are again brought into engagement which will occur at pressures in the neighborhood of 97 to 100 pounds per square inch. The pressure 25 at which the contacts 61 and 62 are closed is lower than the pressure at which these contacts were mechanically opened due to the fact that 30 the spring arm 63 snaps upwardly against the stop arm 73 upon de-energization of the electromagnet 70. This causes the lever arm 55 to rotate farther in a counter-clockwise direction 35 with the contact arm 57 following the screw 56 to bring the contacts 61 and 62 into engagement with the spring arm 63 in its elevated position. In this manner the contacts are mechanically broken upon increasing pressures within the 40 pressure tank and the pressure responsive device 30 as soon as a pressure approximately 105 pounds per square inch or over is attained, whereas the contacts are again made only when the pressure within the tank 25 and pressure responsive means 30 has dropped to a value of 45 approximately 97 to 100 pounds per square inch. This differential of pressure between the points at which the contacts are mechanically broken and then made prevents fluttering or hunting in the control of the intake valve for the compressor.

The making of the contacts 61 and 62 upon retractive rotation of the lever 41 and lever arm 55 causes energization of the solenoid 86 and the opening of the compressor load control valve 22. 50 If the demand for air from the tank 25 is not excessive the retractive movement of the lever 41 through the spring 52 and arm 53 of the lever 50 increases the amount of the fuel delivered to the carbureting means 38 for the engine 12 so that 55 this engine speeds up driving the compressor at a correspondingly increasing rate so as to increase the pressure within the tank 25 until a pressure of approximately 105 pounds is again reached at which point the contacts 61 and 62 are again broken and the intake valve to the compressor closed. The normal operating range of pressures within the air tank 25 is between 80 and 105 pounds per square inch and between approximately 97 to 105 pounds when the load control valve of the compressor is cutting in and out the load on the compressor at which time the compressor is operating at but a small fraction of fuel capacity and at or near idling speeds. At higher speeds, the load control valve does not close and air pressure falls gradually until the engine and compressor reach maximum governed speeds at which time the pressures within the tank range from 80 to 85 pounds per square inch and the compressor is operating at approximately full capacity with wide open throttle on

the engine. In the event of excessive demands for air from the pressure tank 25, there will be a further retraction of the lever 41 and a consequent further increase in the amount of the fuel delivered to the engine which will cause a further speeding up of the engine 12 and compressor 13 and additional delivery of such air from the compressor 13 to the tank 25 to again bring the pressure within the tank 25 within the normal operating range.

10 It will be noted that during the operation of the compressor load control valve 22 that the valve disc 82 is snapped to fully open or fully closed position by the action of either the solenoid 86 or the spring 92. Consequently, there is 15 little or no throttling action of the valve upon air drawn into the compressor. Throttling of air brought into the compressor would be undesirable since this would cause heating of the air which in addition to the heat due to compression of the 20 air within the compressor cylinders would raise the temperature of the delivered air to undesirable values. By avoiding throttling of the air at the intake valve of the compressor the temperature of the delivered air is reduced resulting 25 in less carbonization of oil and insuring proper lubrication of the cylinder walls of the compressor, minimizing the danger of fire and explosion, and at the same time giving longer life of hose and less freezing of tools.

30 As many changes could be made in the above construction and many apparently widely different embodiments of this invention could be made without departing from the scope thereof, it is intended that all matter contained in the above 35 description or shown in the accompanying drawings shall be interpreted as illustrative and not in a limiting sense.

What I claim is:

1. In combination, an air compressor, a load 40 control valve for said compressor operable to open and closed positions independently of the operating parts of said compressor to admit and to prevent admission of air to said compressor, valve operating means normally tending to close 45 said valve, an air tank communicating with said compressor for receiving air delivered by the compressor, motive means for operating said compressor, means for delivering air from the tank, speed control means for controlling the 50 speed of operation of said motive means, valve operating means for overcoming the action of said first named valve operating means and to open said valve, means responsive to the pressure in said tank for controlling the operation of said 55 speed control means, and means operable by said pressure responsive means and in response to a predetermined pressure in said tank for rendering inoperative said second named valve operating means whereby said first named valve operating means closes said valve.

2. In combination, an air compressor, a load 60 control valve for said compressor operable to open and closed positions to admit and to prevent admission of air to said compressor, valve operating means normally tending to close said valve, an air tank communicating with said compressor for receiving air delivered by the compressor, motive means for operating said compressor, means for delivering air from the tank, speed 65 control means for controlling the speed of operation of said motive means, valve operating means for overcoming the action of said first named valve operating means and to open said valve, means responsive to the pressure in said 70

tank for controlling the operation of said speed control means, and means operable by said pressure responsive means and in response to a predetermined pressure in said tank for rendering 5 inoperative said second-named valve operating means whereby said first named valve operating means closes said valve and operable in response to another predetermined pressure in said tank materially lower than said first named predetermined pressure for rendering said second named 10 valve operating means operative to overcome the action of said first named valve operating means and open said valve.

3. In combination, an air compressor, an air 15 intake valve for said compressor operable to open and closed positions, to load and unload said compressor, spring means normally acting to close said valve and prevent admission of air to the compressor, an air tank communicating with 20 said compressor for receiving air discharged from the compressor, motive means for operating said compressor, means for delivering air from said tank, speed control means for governing the operating speed of said motive means, electro- 25 magnetic means operable in the absence of pressures above a predetermined value in said tank for overcoming said spring means and maintaining said intake valve in open position, means responsive to the pressure in said tank for controlling 30 the operation of said speed control means, and means operable by said pressure responsive means and in response to pressure above said predetermined value in said tank for rendering inoperative said electro-magnetic valve operating 35 means whereby said spring means closes said valve.

4. In combination, an air compressor, an air intake valve for said compressor operable to open and closed positions to load and unload said compressor, spring means normally acting to close 40 said valve and prevent admission of air to the compressor, an air tank communicating with said compressor for receiving air discharged from the compressor, motive means for operating said compressor, means for delivering air from said 45 tank, speed control means for governing the operating speed of said motive means, electro-magnetic means operable in the absence of pressures above a predetermined value in said tank for overcoming said spring means and maintaining 50 said intake valve in open position, means responsive to the pressure in said tank for controlling the operation of said speed control means, and means operable by said pressure responsive means and in response to pressures 55 above said predetermined value in said tank for rendering inoperative said electro-magnetic valve operating means whereby said spring means closes said valve and operable in response to another predetermined pressure in said tank mate- 60

rially lower than said first named predetermined pressure for rendering said electro-magnetic valve operating means effective to overcome said spring means and open said valve.

5. In a control system for an air compressor including motive means for operating said compressor, a load control valve for said compressor operable to fully opened and fully shut positions, an air tank for receiving air delivered by said compressor and having means for delivering air therefrom, the combination of, means including an arm rotatable in one direction in response to increasing pressures in said tank and rotatable in the opposite direction in response to decreasing pressures in said tank, valve operating means 10 acting to shut said load control valve, electro-magnetic means operable to overcome said first-named valve operating means and open said load control valve, and a switch operable upon rotation of said arm in said one direction in response to one predetermined pressure in said tank to cause de-energization of said electro-magnetic means whereby said valve operating means becomes effective to shut said load control valve and operable upon rotation of said arm in said 15 opposite direction in response to another pressure in said tank materially lower than said one predetermined pressure to energization of said electro-magnetic means whereby the latter becomes effective to open said load control valve. 20

6. In a control system for an air compressor including motive means for operating said compressor, a load control valve for said compressor operable to fully open and fully shut positions, an air tank for receiving air delivered by said compressor and having means for delivering air therefrom, the combination of, means for controlling the speed of operation of said motive means in response to the pressure in said tank and including an arm rotatable in one direction in response to increasing pressures in said tank and rotatable in the opposite direction in response to decreasing pressures in said tank, valve operating means 35 acting to shut said load control valve, electro-magnetic means operable to overcome the action of said first-named valve operating means and open said load control valve, and a switch operable upon rotation of said arm in said one direction in response to one predetermined pressure in said tank to cause de-energization of said electro-magnetic means whereby said valve operating means becomes effective to shut said load control valve and operable upon rotation of said arm in said opposite direction in response to another pressure in said tank materially lower than 40 said one predetermined pressure to cause energization of said electro-magnetic means whereby the latter becomes effective to open said load control valve. 45

ALLEN C. STALEY. 50
